UNITED STATES PATENT OFFICE.

FRANK O. BADGER, OF BROOKLYN, NEW YORK.

SPRING BED-BOTTOM.

SPECIFICATION forming part of Letters Patent No. 377,419, dated February 7, 1888.

Application filed January 31, 1887. Serial No. 225,985. (No model.)

To all whom it may concern:

Be it known that I, FRANK O. BADGER, of Brooklyn, in the county of Kings and State of New York, have invented certain new and useful Improvements in Spring Bed-Bottoms; and I do hereby declare that the following is a full and exact description thereof, reference being had to the accompanying drawings, and to the letters of reference marked thereon, making a part of this specification, in which—

Figure 1 is a plan view of a complete bed-bottom, different methods of hinging the woven-wire strips being shown therein; Fig. 2, a plan view of a portion of one end of the spring-bottom, on an enlarged scale, illustrating the manner of securing the ends of the woven and straight wires; Fig. 3, a similar view, on an enlarged scale, illustrating a modification in the mode of fastening the ends of the woven wires. Fig. 4 illustrates another modification in the manner of finishing the ends of the woven wires; Fig. 5, an enlarged view of a portion of the wire hinges connecting the woven-wire strips, and Fig. 6 a sectional view of the end plate shown in Fig. 2.

My invention relates to the construction in novel form of a metallic spring bed-bottom which will admit of ready attachment to or detachment from a suitable supporting-frame and of being folded up in small compass for transportation.

It has for its object to produce at a reduced cost a neat clean durable elastic bed-bottom which will retain its form and will not sag unequally under varying weights. This object is attained by forming the bed-bottom of a series of parallel strips of woven wire re-enforced upon their edges by lateral straight wires alternating with parallel independent straight wires serving as the pintle-rods for hinges connecting the strips, the ends of the woven-wire strips being held and united at each end of the structure by clasps hinged together and adapted to be attached to a supporting-frame by means of spiral or helical springs, all as is hereinafter fully described in detail.

In the accompanying drawings, A A is the customary supporting-frame for the bed-bottom.

B B are comparatively narrow elastic strips formed of coiled wires interwoven in the usual

manner from end to end. The wires composing the strips are severally interlaced at each end thereof with perforated plates C C, Fig. 2, or with wire frames D (see Fig. 3) as an equivalent for the plates, and the free ends of the wires projecting beyond each plate or frame are covered and secured and a neat finish imparted thereto by means of a beading, E, preferably of lead or other soft metal or alloy cast or impressed thereon. Before fixing the beading E upon these free ends they may be twisted and bent inward, as shown in the sectional view, Fig. 6. If the beading is to be cast thereon, it is readily accomplished by means of a divided mold to be closed upon the ends of the wires, so as to receive the molten metal and confine it until cooled about and upon the ends of the wires. If the beading is to be secured by clamping it, the sections of beading are cast with sockets or lateral recesses a a, adapted to receive the ends of the wires, as shown in Fig. 6, and when the wires have been inserted into said sockets or recesses the beading is closed and clamped thereon by pressure, or by the use of a hammer.

If preferred, the beading E may be made wide enough to overlap the edge of the plate, as shown in Fig. 4.

The perforated clasp-plates C C, serving as clasps for the ends of the woven-wire strips B B, are hinged together by means of wire loops W W, the hinged connection being formed by bending the ends of the clasp-plates over the wire of the loops, as shown in Figs. 1 and 2, and the hinge-loops W W are extended at either end and twisted at one to form eyes S, (see Fig. 2,) to engage the spiral springs G G, by which the hinged strips are attached to the frame A A in the customary manner, and at the other into a corresponding loop, S', to engage the ends of the straight straining-wires J J of the bed-bottom.

The straight straining-wires J J are stretched parallel with the woven-wire strips B B, as shown in Fig. 1, from the inner eye, S, of each hinge-loop W at one end to the eye S' of the corresponding loop at the opposite end of the bed-bottom to prevent an undue strain upon the woven wires, and the lateral edges of the wire strips are further re-enforced by means of straight wires K K, run through the coils of

the outermost wires in the strip and whose ends are preferably hooked into the clasp-plate C at each end of the strip.

The straining-wires J J are made to serve as pintles for a series of hinges connecting the adjacent strips B B intermediate their ends. These hinges may consist, as is customary, of strap-plates L L, arranged in pairs, and whose inner ends are formed with interlocking-tongues, which are bent around the pintle-wire J, and whose outer ends are bent around the re-enforcing marginal wires K K on each side. Preferably, however, the hinges are formed of two coiled wires, M M, run together upon the pintle-wire J, and which are each bent outwardly at regular intervals in loops N N, (see Fig. 4,) to project each from the same point in opposite directions and embrace the proximate re-enforcing wires K K, these wires K being simply carried through the projecting loops simultaneously with their insertion through the coils of the lateral wire of the strip.

As an equivalent for the perforated clasp-plates C C, hereinbefore described, hinged by wire loops E E, and through whose perforations the ends of the woven wires of the strips B B are interlaced, frames D, of wire, (see Fig. 3,) may be employed and hinged together by plates R. In such case the ends of the woven wires of the strip are interlaced with the bars of the frame D, as shown in Fig. 3, and the straining-wires J are hooked into central holes in the plates R, the ends of the re-enforcing wires K K and of the spiral supporting-springs G G being likewise hooked into apertures in the same plate. (See Fig. 3.)

In constructing the bed-bottom the woven-wire strips B B are first formed and the ends 40 of the wires interlaced in the clasp-plates C C or equivalent clasp-frames, D D, and secured and finished by means of the outer beading, E, applied thereto and secured thereon in manner as described. The clasp-plates C or 45 D at each end of a suitable number of strips are then hinged together, and the straining-wires J J, having the hinge-wires M M run thereon, are hooked into the hinge-loops W W or equivalent hinge-plates, R R. The re- 50 enforcing wires K K are then passed through the lateral coiled wire of each strip and through the loops N of the hinge-wires M M, and made fast at each end to the end plates, C or R, as described. Spiral springs G are now 55 made fast to the hinge-loops W or plates R, whereby the bed-bottom may be secured to the frame A, as required, or it may, by reason of its hinge-connections between the several strips B B, be folded up into very small com- 60 pacts for transportation independent of the frame.

It is evident that the beading E may be co-extensive in length with the width of the woven-wire strips, and may be applied to such 65 a strip independently of the terminal plates or frames, and used to secure the ends of woven

wires which are not interlaced with such plates or frames.

I am aware that it is not new to provide the ends of the woven wires in a bed-bottom 70 with clasps by means whereof to attach the woven wires to the end rails; but these clasps have heretofore consisted of metal plates folded over or laid upon each side of the edge of the piece of woven wire and then riveted down 75 thereon. My invention differs therefrom in that a single plate or frame is used as a clasp, the wires being interwoven with the bars or division-strips between openings in said frame or plate, and that the ends of the wires are 80 concealed and tied by means of a finishing-strip of soft metal cast or compressed upon said ends, so that the latter shall be embedded in the finishing-strip.

I am aware, also, that it is not new to bind 85 the edges of wire-cloth for screens and other purposes with metallic strips bent over said edge and made fast by rivets.

I claim as my invention—

1. The combination, in a spring bed-bottom, 90 of a series of hinged woven-wire strips, clasps securing and uniting the ends of the woven wires in the strips, longitudinal straining-wires interposed between the strips, and hinged connections for the clasps to which the straining-wires are secured, substantially in the manner and for the purpose herein set forth.

2. The combination, with the wires in a woven strip for a bed-bottom, of a terminal plate pierced with two or more parallel rows 100 of holes, which in the one row are opposite the spaces in the other, the ends of each pair of the intertwined wires of the strip being parted and led separately from opposite sides of the plate through two adjacent holes in the first 105 row, then brought together from opposite sides through a single hole in the next row to be again parted, as required, substantially in the manner and for the purpose herein set forth.

3. The combination, with parallel longitudinal strips of woven wire, an interposed longitudinal straight wire, and hinged clasps at the ends of the strips, of one or more intermediate hinges formed upon said straight wire as a pintle and made to couple the two adjacent 110 strips, substantially in the manner and for the purpose herein set forth.

4. The combination, in a hinge for woven-wire bed-bottoms, with a single straight wire serving as a pintle, of two spirally-coiled wires 115 run closely together loosely upon the straight wire and each made to project therefrom in radial arms or loops to serve as the leaves of the hinge, substantially in the manner and for the purpose herein set forth.

In testimony whereof I have signed my name to this specification in the presence of two sub- 125 scribing witnesses.

FRANK O. BADGER.
